CLAIM

The ornamental design for a toy game kit, as shown and described.

DESCRIPTION

FIG. 1 is a perspective view of the toy game kit, showing the new design; the broken lines in the drawings are shown solely to illustrate environment, and form no part of the claimed design;

FIG. 2 is a front view thereof; the broken lines in the drawings are shown solely to illustrate environment, and form no part of the claimed design;

FIG. 3 is rear view thereof; the broken lines in the drawings are shown solely to illustrate environment, and form no part of the claimed design;

FIG. 4 is a left-side view thereof; the broken lines in the drawings are shown solely to illustrate environment, and form no part of the claimed design;

FIG. 5 is a right-side view thereof; the broken lines in the drawings are shown solely to illustrate environment, and form no part of the claimed design; and,

FIG. 6 is a top plan view thereof. The broken lines in the drawings are shown solely to illustrate environment, and form no part of the claimed design.
